DESIGN FOR A PUMPING UNIT

Edgar Voorhees, Kearny, N. J., and Richard A. Niekamp, Dayton, Ohio, assignors to Worthington Pump and Machinery Corporation, Harrison, N. J., a corporation of Delaware, and The Master Electric Company, Dayton, Ohio, a corporation of Ohio

Application April 22, 1938, Serial No. 76,700

Term of patent 14 years

To all whom it may concern:

Be it known that we, Edgar Voorhees and Richard A. Niekamp, both citizens of the United States, residing at Kearny, in the county of Hudson and State of New Jersey, and Dayton, in the county of Montgomery and State of Ohio, respectively, have invented a new, original, and ornamental Design for a Pumping Unit, of which the following is a specification, reference being had to the accompanying drawing, forming part thereof.

In the drawing:

We claim:

The ornamental design for a pumping unit, as shown.

EDGAR VOORHEES.
